United States Patent

Des. 239,375
Patented Mar. 30, 1976

239,375

SAILBOAT HULL

Arthur S. Henry, 5042 Doanoke Ave.,
Irvine, Calif. 92664

Filed Feb. 4, 1974, Ser. No. 439,376

Term of patent 14 years

Int. Cl. D12—06

U.S. Cl. D12—64

FIG. 2

FIG. 4

FIG. 5

FIG. 3

FIG. 1 shows a side elevation view of my new and ornamental design for a sailboat hull;

FIG. 2 shows a top plan view thereof;

FIG. 3 shows a bottom plan view thereof along lines 3—3 of FIG. 1;

FIG. 4 shows a bow elevation view thereof along lines 4—4 of FIG. 1;

FIG. 5 shows a stern elevation view thereof in the direction of lines 5—5; and,

FIG. 6 shows a sectional view thereof along lines 6—6 of FIG. 1.

I claim:

The ornamental design for a sailboat hull, as shown and described.
